AIR HEATING AND CONDITIONING DEVICE
FOR CURING TOBACCO AND THE LIKE

Robert L. Spikes, Farmville, N. C., assignor, by direct and means assignments, to C. L. Hardy Curing Corporation, Maury, N. C., a corporation of North Carolina

Application August 10, 1938, Serial No. 224,188

5 Claims. (Cl. 34—19)

This invention relates to heating devices and has more particularly to do with such devices for use as an air conditioning unit in a tobacco curing barn or other space utilized in the curing of tobacco, the principal object being to improve generally upon heating devices to be utilized for the particular purposes outlined so as to simplify the regulation and control not only of the fuel combustion in the operation of the heater but also in the control of the supply and circulation of the air in the space to be conditioned.

With the foregoing and other objects and advantages to be attained, the invention consists in the general structure and particular parts and combination and arrangement of parts thereof, as hereinafter described and set forth with particularity in the appended claims, reference being had to the accompanying drawings illustrating a practical adaptation of the invention and in which:

Figure 1 is a side elevation of an assembled heating unit;

Figure 2 is a longitudinal vertical sectional view through the unit;

Figure 3 is a top plan view of the unit;

Figure 4 is a cross sectional view, on an enlarged scale, taken on or about the line 4—4 of Figure 1;

Figure 5 is an inverted plan view, and partial horizontal sectional view, taken on or about the line 5—5 of Figure 2; and

Figure 6 is a schematic view illustrating a practical arrangement of a plurality of the heating units as installed in a tobacco curing barn.

Referring now to the drawings, the numeral 10 designates the heating unit as an entirety, the body of the unit being of a general rectangular form and mounted at its opposite ends on transverse base members 11 which, as shown, are heavy plain wooden boards. The body structure is made up of metal sheets which are flanged marginally to give rigidity to the structure and permitting the use of relatively thin gauge metal.

As shown, the body comprises upright end sections 12 formed of rectangular sheets provided with upright angular wings at opposite sides thereof and being flanged outwardly about its lower marginal portions, as at 13, and along their vertical inner marginal portions as at 14. The lower marginal flanges 13 of said end sections 12 are nailed, screwed, or bolted, to the wooden base members 11, as at 15.

Secured to the upper portions of the side wings of the end sections 12, as at 16, preferably by bolts as shown, are opposite elongated side mem-

bers 17 which are flanged along their lower margin, as at 18, and along their middle upper marginal portions, as at 19, said side members 17 being tapered inclined outward from their middle upper portions to their opposite ends and the marginal flanges 19 continuing along said inclined portions.

The end sections 12 and upper side members 17, formed and joined as just above described, constitute, in effect, a substantial main body frame which is reinforced at its middle portion by cross braces 20 and 21, each comprising relatively rigid flat metal bars, the upper cross brace 20 having its opposite end portions bent downwardly at right angles, as at 22, and secured to the adjacent side members 17 by bolts 23. The lower cross brace 21 has its opposite end portions 24 also bent at right angles and abutting the adjacent end portions 22 of the upper cross brace 20 and being secured thereto by the same pairs of bolts 23 which fasten the adjacent portions of the upper brace to the side members 17. These cross braces 20 and 21 span a rectangular opening 25 provided at the top of the main body of the heater between the opposite middle portions of the side members 17 and the inner ends of cover plates 26, the opposite side marginal portions are rebent as at 27, to be fitted slidably over the adjacent inclined flanged marginal portions of said side members 17 and being fastened in place by bolts 28 located at the inner corners of said plates 26 and inserted through registered apertures provided therefore in the coinciding adjacent rebent portions 27 of the plates and the flanges 19 of the side members 17 therebetween.

Located above the main body of the device is a hood 29 which is supported with universal tilting and rotative movement on the cross braces 20 and 21, said hood being in the form of a generally rectangular inverted pan of substantially the same width and length as the main body portion of the device. Preferably, the hood is cross-braced near its opposite ends and substantially midway therebetween, as at 30, while its marginal portion is stiffened by an embossed beading 31 extending therearound. A mounting for the hood, as shown, comprises a stem 32 which is inserted downwardly through aligned apertures provided therefor in the upper and lower cross braces 20 and 21, and being supported on the upper cross brace 20 by a cross pin 33 which may be an ordinary cotter pin. At the upper end of the stem 32 is a spherical enlargement 34 secured fixedly thereto or formed integrally therewith. The spherical head 34 of the stem 35

32 is clamped between a spider 35 and a retaining plate 36 which is attached to the spider by bolts 37 with adjustable tension springs 38 sleeved on the bolts and interposed between said plates 36 and the securing nuts 39 of the bolts. The spider 35 and retaining plate 36 are obviously provided with registered apertures of lesser diameter than the head 34 of the stem 32, affording opposed seats in which the head 34 is held frictionally by the tension of the springs 38, yet permitting universal tilting and rotative movement of the hood at the will of the operator. As shown more clearly in Figure 4, the spider has four diametrically opposed arms, two of which extend longitudinally of the hood and upwardly into engagement therewith, as at 40, and being secured thereto by bolts 41, the other pair of arms 42 extending laterally in a lower plane and being secured at their ends to the adjacent portions of the hood by bolts 43.

Any desirable or necessary number and suitable type of fuel burner element may be provided in the device. As shown more clearly in Figures 1 and 2, four of these elements of the oil-burner type are indicated conventionally, as at 44, the same being spaced apart and arranged in a longitudinal row with their respective oil-supply and flame controls 45 serving as supports therefor, said controls being mounted on a horizontal supply pipe 46 which is supported at its opposite ends on the base members 11 and fastened thereto by suitable clips or other fastening devices as at 47. In this connection, it is noted that in the installation of a plurality of the heating devices of the present invention, for example, in a tobacco curing barn or the like, for which purpose the devices are primarily intended, the same is practically accomplished by first placing the boards or base members 11 on the floor at the respective locations where the several heaters are to be placed and then mounting on said members 11 assemblies of the pipes 46 with the burner elements 44 mounted thereon as separate units over which the heater bodies are next placed and secured to said members 11 by the fastening means 15, it being understood that the lower edge portions of the end members 12 of the bodies are notched, as at 48, to fit over adjacent end portions of the pipes 46 with ample clearance therebetween. It is further noted that the respective oil-supply pipes 46 of the several units are connected to a main supply by pipe 49 which is in turn connected to a source of oil-supply (not shown). A conventional installation and hook-up of the heating devices for air conditioning a tobacco curing barn or the like is shown diagrammatically in Figure 6, the side walls of the barn being shown in horizontal section and designated by the numeral 50.

By the peculiar construction of the main body of the heating unit 10, as herein shown and described, elongated rectangular openings 51 are provided at opposite sides of the device of relatively large area and through which the air is supplied to the burner elements 44 in sufficient quantity to support combustion at all times. Convenient access is also afforded through these side openings 51 for adjustment of the respective fuel and flame controls 45 of the burners. The heated air in the upper portion of the body of the unit passes out through the central opening 25 in the top of the body and is deflected laterally by the overhanging hood 29 which, as hereinbefore described, may be tilted on its universal mounting so as to deflect the preponderance of

the heated air in any desired direction as it is discharged from the opening 25.

In conditioning the air within a tobacco curing barn or other enclosure used in the curing of tobacco and for other purposes it is not only essential that the air be heated but it is also necessary to admit air from the outside and in regulated volume. Provision for supplying outside air in connection with the heating device is a most important feature of the present invention, and to this end an air duct 52 is located in one end portion of the main body of the heater and extended outwardly and downwardly through an opening in the wall 50 of the barn or other enclosure, as the case may be. This duct 52 in every installation is disposed at an inclination which is upward from its outer air receiving end to its inner air discharge end, the angle of inclination varying in different installations and depending principally upon the particular height of the usual brick or concrete base or foundation which supports the side wall 50 of the barn, in some instances, or depending upon the permissible distance above the floor where the opening may be provided in the wall 50 for the projection of said duct 52 therethrough. In any case, however, a substantial inward and upward inclination is necessarily maintained so that a circulation of air is induced inwardly through the duct 52 when the latter is heated, as occurs when the burner elements 44 are in operation.

For effecting the angular adjustment of the duct 52 it is swingably supported at its inner end adjacent the inner marginal portion of the overlying cover plate 26, the attachment of the duct to the plate being preferably by means of a bolt 53 which is inserted with a rather loose fit through registered apertures provided therefor in the adjacent portions of the plate and duct, while to permit up and down swinging movement of the duct on said bolt 53 the end wall portion of the adjacent upright member of the body is provided with a vertically elongated opening 54 through which the outer end portion of the duct is extended.

In practically all instances the inner end portion of the duct 52 terminates closely adjacent to the centre opening 25 of the heater body, but said duct may vary in length, depending upon the particular installation of the heater. Obviously, the duct may be made in one piece or comprise two or more sections telescoped or otherwise joined endwise together.

For controlling the volume of air passing through the duct 52 and for cutting off the supply of air entirely therethrough, a gate 55 is provided at the outer end of the duct. Preferably, as shown, this gate comprises a generally circular plate of ample diameter to cover the opening in the adjacent end of the duct, said gate having a peripherally offset portion or ear 56 which is apertured for the reception of a pivot-bolt 57 which is in turn secured in an aligned aperture provided therefor in an angular supporting bracket 58 riveted on the adjacent end portion of the duct. For reinforcing the gate 55 and at the same time providing a handle for conveniently manipulating it, an angular piece 59 is riveted on the outer face of the gate, one end portion of said piece 59 extending in overlapping relation to the ear 56 of the gate and having a coinciding aperture for the reception of the pivot bolt 57.

In the operation of the heater the heated air in the upper portion of the main body of the unit 75

is discharged through the central opening 25 and deflected in the desired direction from the unit by the adjustment of the hood 29 as hereinabove described, and at the same time, if the gate 55 at the outer end of the duct 52 be opened, the air in the duct being heated as it is due to the particular location of the duct in the upper portion of the main body and set at an inward and upward inclination, the circulated air as induced in the duct is discharged into the stream emanating from the opening 25 with a dehumidifying or other tempering effect on the air within the barn or enclosure, depending upon the degree to which the tobacco or other content is to be treated and the amount of moisture given off in the dehydration of the bulk being treated; it being of course understood that from time to time during operation of the heater or heaters as installed, the gate or gates 55 will be adjusted to vary the volume of air passing through the duct or ducts.

While the structure herein illustrated and described embodies a practical adaptation of the invention, it is obvious that considerable modification may be made therein within the spirit and scope of the invention as defined by the appended claims. The invention therefore is not limited to the specific construction and arrangement shown in the accompanying drawings.

30 What is claimed is:

1. In a heating device of the character described, an elongated, generally rectangular, hollow main body having air heating means therein, said body having horizontally elongated openings in its opposite longitudinal side walls and a top closure above said longitudinal side openings and the air heating means, the top closure being provided with a central outlet opening for the heated air, and an air duct tube located in the upper portion of the body substantially in a vertical plane coincident with the longitudinal axis of the body and entering through an end wall of the body and extending at an upward inclination throughout its length from said body end wall, the duct tube being disposed with its major upper portion in the effective zone of created heat above the heating means whereby the duct tube and the air therein is heated and the heated air caused to flow upwardly in the duct tube and the upper end of the duct tube being open and terminating within the hollow body and adjacent the heated air outlet of the body top closure.

2. In a heating device of the character described, a hollow main body having air heating means therein and provided with an outlet opening at its top for the heated air, an inwardly and upwardly inclined air duct hingedly supported at its inner end in the upper portion of said body whereby to be swingable vertically for angular adjustment, said duct extending be-

yond the adjacent end of the body whereby to be projected operably through and beyond an adjacent building wall, and a gate on the outer end portion of said duct for regulating capacity of said duct and closing the duct, at will.

3. In a heater of the character described, a main body having air heating means therein and provided with an outlet opening at its top for the heated air, a hood mounted above the outlet opening with universal adjustment for directing the air discharged from the heater in different directions laterally from the heater, an inwardly and upwardly inclined air duct located within the upper portion of the heater with its inner end hingedly attached to the top of the body adjacent the outlet opening of the heater, and extending through the effective heat zone of the heater.

4. A heating device of the character described, comprising a generally rectangular elongated main body section having elongated rectangular openings in its opposite side walls, the top of said body having a central outlet opening for air heated in the body, the top sloping downwardly from opposite sides of said outlet opening to the ends of the body, burner elements arranged in longitudinal series in the lower portion of the body, an inwardly and upwardly inclined air duct extending into the heated zone in the upper portion of said body, the inner end of said duct being hingedly supported on the top of the body adjacent the outlet opening of the top whereby to be swingable vertically for angular adjustment, the lower end of said duct extending beyond the adjacent end of the body and provided with a gate for regulating the capacity of the duct and closing the duct at will.

5. A heating device of the character described, comprising a generally rectangular elongated main body section having elongated rectangular openings in its opposite side walls, the top of said body having a central outlet opening for air heated in the body, the top sloping downwardly from opposite sides of said outlet opening to the ends of the body, burner elements arranged in longitudinal series in the lower portion of the body, an inwardly and upwardly inclined air duct extending in the heated zone in the upper portion of said body, the inner end of said duct being hingedly supported on the top of the body adjacent the outlet opening of the top whereby to be swingable vertically for angular adjustment, the lower end of said duct extending beyond the adjacent end of the body and provided with a gate for regulating the capacity of the duct and closing the duct at will, and universally adjustable deflector means located above the body for directing the air discharged from the outlet opening of the body in different lateral directions at will.
